UNITED STATES PATENT OFFICE

148,330

DESIGN FOR A JACKET OR SIMILAR ARTICLE

Samuel Scheidlinger, Jackson Heights, N. Y.

Application June 13, 1947, Serial No. 139,645

Term of patent 3½ years

(Cl. D3—4)

To all whom it may concern:

Be it known that I, Samuel Scheidlinger, a citizen of the United States of America, residing in Jackson Heights, county of Queens, State of New York, have invented a new, original, and ornamental Design for a Jacket or Similar Article, of which the following is a specification, reference being had to the accompanying drawing, forming part thereof.

In the drawing:

The essential feature of my design resides in the combination on the jacket disclosed of the specific ornamentation applied to the breast portions as shown.

I claim:

The ornamental design for a jacket or similar article, substantially as shown and described.

SAMUEL SCHEIDLINGER.
